UNITED STATES PATENT OFFICE

MALCOLM W. ANDERSON, OF MIAMI, FLORIDA

LEGGINGS

Application filed July 11, 1929. Serial No. 377,491.

This invention relates to leggings and has for its object to provide a device of this character which is more efficient in use, less costly to manufacture and more pleasing in appearance than those heretofore proposed.

With these and other objects in view the invention consists in the novel details of construction and combinations of parts as will be more fully hereinafter disclosed and particularly pointed out in the claims.

Referring to the accompanying drawings forming a part of this specification in which like numerals designate like parts in all the views,—

13 Fig. 1 is a perspective view of a leg with the legging partially applied thereto;

Fig. 2 is a view showing the legging opened out and laid flat to more clearly illustrate the relationship of the parts; and

20 Fig. 3 is a perspective view of a leg with the legging completely applied.

In order that this invention may be the better understood it is said that heretofore leggings have been provided which are either 25 form-fitting or else have been provided with fastening means which necessitated considerable work upon the part of the wearer in putting on or taking off. In other words, such leggings have had long rows of buttons, or a long lacing which had to be wound through eyelets or over hooks, or the leggings have been formed of relatively narrow strip material which had to be wound spirally about the leg. The principal object of this invention is to provide leggings avoiding such cumbersome construction and tedious securement as have been common with the devices heretofore proposed, thus providing a legging which may be taken off with the least possible effort.

40 This particular legging forming the subject matter of this invention may be made of any suitable material, preferably rubberized material, the feature being to provide a material which is water-proof, and which will be warm when used in winter. In its simplest form the legging constitutes a sheet of material which need not be particularly tailored or fashioned to exactly conform to the contour of the leg but the legging does contemplate a

strengthening rib extending along one vertical edge portion to aid in securing the legging in place. The rest of the legging is more or less cut on the bias to provide an appreciable flare at one end and provided with suitable tucks and gathers to create a more artistic draping of said flare. A separate piece of material is sewed or otherwise securely fastened to the main body portion of the legging at the point where the legging would cover the instep of the foot, and thus more or less seal the front top of the shoe to prevent entry of water.

Referring to the drawings the legging proper is indicated by the numeral 1 along one vertical edge of which is securely fastened a rigid strip of material 2 which may be either metal, fiber, or any other stiffening medium. This strip is intended to extend from a point just below the knee to the bottom edge of the legging and may be given a slight bowed formation following the contour line of the calf of the leg, although it is to be understood that when the legging is in place this rib will be on the inner side of the leg. The upper edge portion of the legging is cut so that when it is fastened to the leg the upper edge will lie in a substantial horizontal plane about the leg either above or below the knee. If the legging is to extend to a point above the knee then the reinforcing member 2 will not extend above a point just below the knee to permit flexibility in the upper portion of the legging when the knee is flexed. The advantage of the legging extending above the knee should be apparent but in this connection it should be stated that it has been found quite advantageous when the wearer is seated out of doors. The shorter legging, such as illustrated in Fig. 2 of the drawings, is provided with a knee cap 3 which is secured along the upper edge portion 4 of the legging, and this knee portion may be of the same material as the legging or could be of other material such as leather, the purpose being merely to protect the knees.

45 Referring more particularly to Fig. 2 it will be seen that the legging has a substantial width, or a width which is greater than the

100

vertical dimension of the legging when in place, the main body portion of the legging on the side opposite to the edge containing the reinforcing member 2 being cut on a bias 5 to provide an extending portion or flare 5 as clearly indicated. The extra width of the legging is provided to allow a secondary wrapping thereof about the leg, as well as to provide the flare 5 which is of pleasing 10 appearance to the eye. The lowermost edge of the legging is provided with a flap 6 at a point opposite the knee cap 3 and said flap being preferably preformed and stitched as at 7 to the main body portion of the legging 15 to provide a fulness adapted to closely fit over the upper edge of the shoe and cover the instep, all as will be clear from Fig. 1.

The reinforcing member 2 may stop at the lower edge portion of the legging but it has 20 been found advisable to extend the same in order to cause the legging to more closely fit the ankle. This has preferably been done by providing an extending portion of said member, curved laterally from the main body 25 portion of the reinforcing member as indicated at 8, and thence downwardly as at 9, terminating in an inturned stirrup 10 which is adapted to rest on the underside of the shoe adjacent the heel. By forming this reinforcing member with its laterally curved and 30 depending portions the weight of the legging is confined to a straight line following the main body portion of the reinforcing member. The legging at the lower corner adjacent the reinforcing member is provided with 35 a flap 12 extending in the direction shown in Fig. 2 said flap being for the purpose of adding weight to the legging at the bottom edge thereof, and fitting around the back of the 40 leg just above the heel for engagement by the secondary wrapping to assist in holding the legging in position when applied to the leg, and thus preventing the legging from moving forward and becoming displaced.

45 The upper edge portion of the legging is provided with a supporting band 13 which extends the full length of said edge portion. On this band, and in line with the reinforcing member 2, is a fastening means such as the button 14 adapted to engage a companion fastening means, such as a button-hole 15, disposed on said band at a distance to permit a close confinement of the upper edge of the legging around the leg below the knee. Between the button 14 and the buttonhole 15 50 there is secured to the band 13 a fastener such as a button 16 which is adapted to engage a companion fastener such as the button-hole 17 at the end of the band farthest from the reinforcing member.

55 Instead of the buttons and button-holes just mentioned, other fastening means could obviously be substituted including the well known snap fastener, and in order that the legging may fit different sized legs provision

may be made for a plurality of fastening elements as will be readily understood.

The application of the legging to the leg is as follows. The legging is applied with the stirrup 10 placed under the shoe in advance 70 of the heel with the reinforcing member 2 extending vertically along the inner side of the leg. The main body portion of the legging is then wrapped or folded about the leg and the button-hole 15 engaged by the button 14. This completes a single fold of the legging about the leg, but the remaining portion of the legging is continued around the leg forming a second fold across the front thereof, and the button hole 17 engaged by the button 16 75 which last mentioned fastening means is located on the outer side of the leg, leaving the flare 5 free. In applying the legging the flap 12 is tucked in under the enfolding portion of the legging. For additionally securing the legging there is provided a fastening means near the bottom such for example as the depending hook 20 carried by the reinforcing rib 2 adapted to be engaged by the eye 21 carried by the flaring or the enfolding portion of the legging. After the hook and eye are drawn into engagement, the legging is then secured in place by the fastening means disposed on the band 13.

80 It will thus be seen that this legging is adapted to be supported entirely from the band 13 which closely fits the leg below or above the knee, which particularly distinguishes this legging from others whose fastening means extend to the bottom thereof, and which are supplied with strap loops which have to be unfastened or through which the foot must be passed.

85 In fact all one has to do to remove this legging is to unfasten the buttons 14 and 16 both of which are at the upper end of the legging and therefore in easy reaching distance. After the second button or other means, has been unfastened, a slight pull by the hand, or a kick of the foot, will cause the legging to leave the leg. It should be stated 90 that leggings are prone to become soiled at their bottoms and become particularly so from mud and slush, but with a legging made in accordance with this invention such a condition is not so exasperating since this legging can be readily removed with no soiling of the hands, which need never touch the bottom of said legging during its removal.

95 From the foregoing descriptions it will therefore be seen that this invention contemplates a legging having in combination a main body portion 1 adapted to be wrapped about the leg, and fastening means disposed at the top of said body portion such as the buttons 14 and 16 for supporting the legging 100 when in use. The fastening means performs the dual function of not only securing the legging about the leg, but supporting the legging. Further the main body portion car- 105

ries an extension and flare which are adapted to form a second thickness about a portion of the leg, preferably the shin portion where added protection is needed, and this extension is provided with additional fastening means in the button 16 for securing the same to the main body portion, leaving the triangular flare 5 unconfined. The main body portion is provided with a reinforcing member disposed along one edge thereof, the bottom of said member being laterally extended in a direction toward the toe to fit around the ankle bone, and then the forward extension is bent downwardly and in under the shoe to form a stirrup which coacts with the heel and sole of the shoe to form a rigid brace for the legging. Also fastening means comprising a hook 20 and an eye 21 may be provided to constrict the lower portion of the legging about the ankle.

The flap 12 in passing about the rear of the leg immediately above the heel is given a substantial bend due to the relative thin dimension of that portion of the leg and when the secondary wrapping is drawn over said flap in applying the legging, there will be created a substantial resistance tending to prevent the displacement of the flap with relation to the leg. This relation of parts further assists in maintaining the legging in correct position during use.

It is obvious that those skilled in the art may vary the details of construction as well as arrangement of parts without departing from the spirit of the invention and it is therefore not desired to be limited to the foregoing except as may be required by the claims.

What is claimed is:—

1. In a legging the combination of a main body portion of a length to extend from the ankle to the knee and of a width to pass around a leg throughout said length, said portion provided with an extension carrying a flare; and fastening means carried by said body portion and said extension to secure the same at the inner and outer upper extremities of the extension leaving the flare unconfined, said means adapted to coact with the leg to support the legging.

2. In a legging the combination of a main body portion of a length to extend from the ankle to the knee and of a width to pass around a leg throughout said length forming a single thickness about the leg, said portion provided with an extension carrying a flare and adapted to form a second thickness about a portion of the leg; means to secure the upper outer end of said extension to the top of said body portion; and fastening means carried by said body portion and said extension, said last named means adapted to coact with the leg to support the legging.

3. In a legging the combination of a main body portion of a length to extend from the

ankle to the knee and of a width to pass around a leg throughout said length forming a single thickness about the leg, said portion provided with an extension carrying a flare and adapted to form a second thickness about a portion of the leg; means to secure the outer upper end of said extension to said body portion leaving said flare unconfined; and fastening means carried by said body portion and said extension, said last named means adapted to coact with the leg to support the legging.

4. In a device of the character described the combination of a main body portion adapted to be wrapped about the leg; a reinforcing member disposed along one edge of said body portion and adapted to extend beneath the foot; and fastening means disposed at the top of said body portion for supporting the device on the leg.

5. In a device of the character described the combination of a main body portion adapted to be wrapped about the leg; a reinforcing member for said body portion, said member having an offset extension adapted to pass around the ankle bone and beneath the foot; and fastening means disposed at the top of said body portion for supporting the device on the leg.

6. A legging comprising a substantially rectangular main body portion adapted to form a covering of single thickness when wrapped about a leg, said portion provided with an extension at the lower corner of one side thereof adapted to engage the back of the leg immediately above the heel, and said portion further provided with a second and larger extension at the other side edge thereof of said last named extension adapted to form a second protective covering of a portion of the leg; and means to secure said legging to a leg.

7. A legging comprising a main body portion providing a single wrapping for a leg, said portion having an extension providing a second wrapping over the shin, fastening means for securing the legging to the leg, and a reinforcing member along one edge of said portion adapted to engage a fastener to constrict the legging about the ankle.

8. In a legging the combination of a main body portion provided with an extension; and fastening means adjacent the top edges of said portion and said extension and disposed at the inner and outer extremities of said extension, said means adapted to coact with the leg to support the legging in single thickness around the calf and double thickness over the shin.

9. In a legging the combination of a main body portion of a length to extend from the ankle to the knee and of a width to pass around a leg throughout said length, said portion provided with an extension carrying a flare; and dual fastening means one of which

is disposed between said body portion and
said extension and the other of which is dis-
posed between the outer extremity of said ex-
tension and said body portion leaving the
flare unconfin'd, the first mentioned of said
means adapted to coact with the leg to sup-
port the legging.

In testimony whereof I affix my signature.
